(57) **CLAIM**

The ornamental design for a turf cutting reel, as shown and described.

DESCRIPTION

FIG. 1 is a perspective view of a turf cutting reel showing our new design;

FIG. 2 is a front view thereof;

FIG. 3 is a left side view thereof; and,

FIG. 4 is a right side view thereof.

The broken line showing of various surface features is included for the purpose of illustrating portions of the turf cutting reel and forms no part of the claimed design.
